(57) CLAIM

The ornamental design for a deck of playing cards as shown and described.

DESCRIPTION

FIG. 1 is a front plan view of the first card, part of a deck of playing cards, showing my new design;

FIG. 2 is a front plan view of the second card, part of the deck of playing cards, showing my new design;

FIG. 3 is a front plan view of the third card, part of the deck of playing cards, showing my new design;

FIG. 4 is a front plan view of the fourth card, part of the deck of playing cards, showing my new design;

FIG. 5 is a front plan view of the fifth card, part of the deck of playing cards, showing my new design;

FIG. 6 is a front plan view of the sixth card, part of the deck of playing cards, showing my new design;

FIG. 7 is a front plan view of the seventh card, part of the deck of playing cards, showing my new design;

FIG. 8 is a front plan view of the eighth card, part of the deck of playing cards, showing my new design;

FIG. 9 is a front plan view of the ninth card, part of the deck of playing cards, showing my new design;

FIG. 10 is a front plan view of the tenth card, part of the deck of playing cards, showing my new design;

FIG. 11 is a front plan view of the eleventh card, part of the deck of playing cards, showing my new design;

FIG. 12 is a front plan view of the twelfth card, part of the deck of playing cards, showing my new design;

FIG. 13 is a front plan view of the thirteenth card, part of the deck of playing cards, showing my new design;

FIG. 14 is a front plan view of the fourteenth card, part of the deck of playing cards, showing my new design;

FIG. 15 is a front plan view of the fifteenth card, part of the deck of playing cards, showing my new design;

FIG. 16 is a front plan view of the sixteenth card, part of the deck of playing cards, showing my new design;

FIG. 17 is a front plan view of the seventeenth card, part of the deck of playing cards, showing my new design;

FIG. 18 is a front plan view of the eighteenth card, part of the deck of playing cards, showing my new design;

FIG. 19 is a front plan view of the nineteenth card, part of the deck of playing cards, showing my new design;

FIG. 20 is a front plan view of the twentieth card, part of the deck of playing cards, showing my new design;

FIG. 21 is a front plan view of the twenty-first card, part of the deck of playing cards, showing my new design;

FIG. 22 is a front plan view of the twenty-second card, part of the deck of playing cards, showing my new design;

FIG. 23 is a front plan view of the twenty-third card, part of the deck of playing cards, showing my new design; FIG. 24 is a front plan view of the twenty-fourth card, part of the deck of playing cards, showing my new design; FIG. 25 is a front plan view of the twenty-fifth card, part of the deck of playing cards, showing my new design; FIG. 26 is a front plan view of the twenty-sixth card, part of the deck of playing cards, showing my new design; FIG. 27 is a front plan view of the twenty-seventh card, part of the deck of playing cards, showing my new design; FIG. 28 is a front plan view of the twenty-eighth card, part of the deck of playing cards, showing my new design; FIG. 29 is a front plan view of the twenty-ninth card, part of the deck of playing cards, showing my new design; FIG. 30 is a front plan view of the thirtieth card, part of the deck of playing cards, showing my new design; FIG. 31 is a front plan view of the thirty-first card, part of the deck of playing cards, showing my new design; FIG. 32 is a front plan view of the thirty-second card, part of the deck of playing cards, showing my new design; and, FIG. 33 is a back plan view of FIG. 1, with the back views of FIGS. 2-32 being identical and therefore, not shown in the drawings.
